CLAIM

The ornamental design for a post clamp bracket, as shown and described.

DESCRIPTION

FIG. 1 is a front view of a post clamp bracket showing my new design;

FIG. 2 is a left side view thereof;

FIG. 3 is a right side view thereof;

FIG. 4 is a rear view thereof;

FIG. 5 is a top front-left angled isometric view thereof;

FIG. 6 is a bottom rear-right angled isometric view thereof;

FIG. 7 is a top-down view thereof; and,

FIG. 8 is a bottom-up view of a post clamp bracket.
